CAN OPENER

Matthew H. Meade, North Wilkesboro, N. C.

Application April 24, 1941, Serial No. 390,183

4 Claims. (Cl. 30—16)

The present invention relates to improvements in can opening devices designed particularly for forming pouring openings in a can end.

An object of the invention is to provide a can opener of generally improved design.

Another object of the invention is the provision of a can opening device which is constructed so that pouring openings may be quickly and easily formed in the top or end of a can.

A further object of the invention is to provide a can opening device which can be readily positioned on a can to form diametrically opposite pouring and vent openings in an end thereof.

Still another object of the invention is the provision of a can opening device of the aforesaid character which is constructed to simultaneously puncture a can end at two points to provide pouring and vent openings therein.

Still another object of the invention is to provide a can opening device which is operable to open cans of more than one size.

A still further object of the invention is the provision of a can opening device of the above character which is relatively simple and durable in construction and reliable in use.

Other objects and advantages of the invention will become apparent as the description progresses.

In the accompanying drawing forming a part of this specification and in which like numerals are employed to designate corresponding parts throughout:

Figure 1 is a side elevational view of a preferred form of the device in its initial position on the end of a can.

Figure 2 is a similar view partly in section showing the device in can gripping position.

Figure 3 is a top plan view of the same with part of the handle broken away.

Figure 4 is a vertical sectional view showing the arrangement of the device on completion of the hole forming operation.

Figure 5 is a fragmentary sectional view taken on line 5—5 of Figure 2.

Figure 6 is a transverse section taken on line 6—6 of Figure 5.

Figure 7 is a fragmentary detail elevational view of the handle member.

Figure 8 is a side elevational view of a modified form of the device, and

Figure 9 is an end elevational view of the same.

Referring to Figures 1 to 7 inclusive, wherein is illustrated a preferred embodiment of the invention, C designates a clamping section of the

device having a flat body plate 10 formed at one end with laterally projecting fingers 11. At opposed sides of the plate 10 are formed right angularly projecting complementary flanges 12 apertured to engage the ends of a pivot pin 13 mounted transversely of the plate. The flanges 12 are formed integral with a pair of outwardly diverging legs 14 formed at their outer ends with hooked jaw-forming projections 15 preferably shaped to provide an acute angled gripping edge 16.

To the pivot pin 13 is connected the inner end of an elongated flat lever bar 17, of a length sufficient to form an operating handle. The inner portion of this bar is provided with a slot 18 at which portion the bar is bent longitudinally to form a pair of transversely spaced bearing sleeves 19 embracing the end portions of the pivot pin 13. The inner bent portion of the lever bar is prolonged to form an arcuately bent cutter element 20, curving away from the outer face of the bar at the pivoted end and preferably of triangular contour, providing beveled side edges tapering to a sharp point at the outer extremity. This cutter is, therefore, fixed with relation to the lever 17.

Pivotedly connected with the clamping section C is a complementary clamping member 21 in the form of an elongated flat arm of angular formation having its inner end apertured to pivotally engage the center portion of the pin 13. At its outer end the arm 21 is formed with a downwardly hooked jaw-forming portion 22 shaped so that its inner edge provides a protruding lip 23. Adjacent to and inwardly of the jaw 22 the lower edge of the arm 21 is shaped to form a triangular-shaped projection forming an inwardly spaced jaw 24.

To an angular bracket 25, secured to one face of the handle lever 17, adjacent its inner end, is connected, by a pivot 26, the inner end of a bar 27 disposed above and parallel with the arm 21. This upper bar is curved longitudinally and carries a pair of spaced laterally projecting studs 28 and 29 on its outer end portion. To the outermost stud 28 is connected one end of a lever 30 approximately in the form of a bell crank lever having its relatively long arm disposed so that its outer apertured end turns about the stud 28 while its inner end is apertured to turn about a stud 31 secured to and projecting laterally from the clamp arm 21. The inner portion of the lever 30 is formed with a hooked cutter forming spur 32 designed to puncture a can end and form an elongated slot therein. To the stud 29 is

connected the outer slotted end of a companion bell crank lever 33 having its inner end pivotally connected with a stud 34 on the clamp arm and formed with a cutter spur 35.

About one sleeve section 19 of the handle lever is coiled a spring 36 having one end extended through a hole 37 in the arm 21 and its opposite end engaging a notch 38 in the outer edge of the plate 10, this spring functioning to yieldingly retain the clamp arm 21 in a predetermined angular position with relation to the clamp member C. As clearly shown at Figure 1 the spring 36 normally urges the inner end portion of the angular arm 21 against the outer portion of the plate 11 so that the inner edge portion of this arm is yieldingly held so as to assume a predetermined obtuse angled relation with the plate 10 and the extension legs 14, although movable about the pivot 13 to widen this angle, as illustrated at Figure 2. About the opposite bearing sleeve 19 of the handle lever is coiled a second spring 39 having one end fitted in a notch at the inner edge of the plate and the opposite end bent to engage the inner portion of the cutter 20, as indicated at 40; so that it acts to yieldingly swing the projecting legs 14 of the clamp section C to a predetermined outward position with relation to the handle lever. With this in mind the outer end of one of the bearing sleeves 19 is cut inward to form an arcuate recess 41 into which projects a pin 42 fixed to and projected inwardly of one of the flanges 12 to limit the angular movement of the clamp section with reference to the handle and to yieldingly retain the same at approximately right angular positions as shown at Figure 1.

The device normally assumes the arrangement and is initially fitted on the top end of the can as shown at Figure 1, with the complementary jaws 20 of the clamp section C disposed against arcuately spaced points of the peripheral seam and the diametrically opposed front jaw 22 placed on the margin of the top. The handle 17 is then swung inward toward verticality so as to spread apart or open the clamp sections and their jaws from their normal angularly contracted arrangement and slide the jaw 22 over the rim or peripheral margin of the can top to grip the same, as illustrated at Figure 2. The handle 17 is then swung quickly outward and downward, in a clockwise direction, without depressing the intermediate pivot joint of the clamp sections, with the result that the curved relatively large triangular-shaped cutter 20 and the hooked cutter 32 are simultaneously swung to downward positions into engagement with the top and, during continued downward movement of the handle, puncturing the cover at diametrically opposite points. The small cutter 32 forms a comparatively narrow slot disposed radially in one margin of the can end 60 while the larger cutter 20 cuts a wedge-shaped part of the cover therefrom and rolls the same downwardly and inwardly as shown to advantage at Figure 4. This cutting action provides a pair of cleanly cut holes affording a vent opening of relatively small area at one point of the top and a relatively large pouring opening in an opposite portion thereof.

The device may be similarly applied, without changing its structure, to a can of decreased diameter by gripping that portion opposed to the diverging jaw elements with the jaw 24 spaced inwardly on the clamping arm 21; in which case the vent slot is cut by the hooked cutter spur 35 simultaneously with the cutting of the pouring 75

opening. While this device may be advantageously used in connection with cans of varying construction and different types of end sealing joints or seams it is especially adaptable for cans known as sealed cans in which the ends are equipped with peripheral flanges slidably fitted over the ends of the circumferential wall and sealed by solder. This type of end connection, widely used in canning milk and the like, affords but a thin peripheral flange or beading about the can. However, my improved clamping and jaw means very effectively engages such rim construction and enables very convenient opening or puncturing of the ends of such a can. Furthermore, the device is very easily handled and manipulated to effect the puncturing action and, due to the arrangement of the three gripping jaws, accurately positions itself to cut the openings in diametrically opposed positions to insure efficient pouring of the contents of a can. As will be noted, the device is firmly held in place by the spaced apart jaws 15 at one side and the diametrically opposed jaw 22 while undue tilting of the handle lever is prevented by the laterally projecting fingers 11.

In a modified form of the device shown at Figures 8 and 9 an angular clamping arm 43 is pivotally connected with the double jawed clamping section 44 and is serrated along the major 30 length of its top edge to form teeth 45.

Slidably mounted on the arm 43 is a member 46 embodying a flat elongated bar formed with a slot 47 shaped to slidably receive the arm therethrough. The inner or lower end of the slide member is formed with a tapered transversely curved jaw projection 48 directed inwardly of the pivoted clamping sections for gripping the edge of a can. A pin 49 fixed transversely in the end portion of the arm 43 forms an abutment 40 limiting the outward movement and disconnection of the slide element 46. Thus, the member 46 can be adjustably positioned at any desired position along the arm, in an inclined arrangement and held in place by the teeth 45.

This form of the opener is designed for connection with cans varying greatly in size and, by movement of the handle lever indicated at 50, operates a curved cutter 51 to puncture the can end and form a pouring opening therein.

It is to be understood that the forms of my invention herewith shown and described are to be taken as preferred and modified examples of the same and that various changes relative to the material, size, shape and arrangement of parts may be resorted to without departing from the spirit of the invention or the scope of the subjoined claims.

Having thus described my invention, I claim:

1. In a can opening device, a clamp member having spaced apart can gripping jaws, a clamping arm having a gripping jaw on its outer end, a pivot connecting the inner end of the clamping arm with the said clamping member, an operating lever connected to the said pivot, means yieldingly urging the said clamping elements to contracted gripping positions, a cutter formed on and projecting from the operating lever, a cutter pivotally mounted on the clamping arm, and a bar connecting the last-mentioned cutter with the lever whereby the said lever is operable to simultaneously actuate the cutters for puncturing the can end at diametrically opposed points.

2. In a can opening device, a clamp member having spaced apart can gripping jaws, a clamp-

ing arm having a gripping jaw on its outer end, a pivot connecting the inner end of the clamping arm with the said clamping member, an operating lever connected to the said pivot, spring means yieldingly urging the said clamping elements to contracted positions, a cutter formed on and projecting from the operating lever, a cutter pivotally mounted on the clamping arm, a bar connecting the last-mentioned cutter with the lever whereby the said lever is operable to simultaneously actuate the cutters for puncturing the can end at diametrically opposed points, and means for yieldingly retaining the operating lever in a predetermined angular relation with the clamping member.

3. In a can opening device, a clamping section having spaced jaws adapted to grip the rim of a can end, a clamping arm having a jaw formed at its outer end for gripping the said can rim, a pivot connecting the inner end of the arm with the clamp section, a spring disposed to normally retain the said clamp arm and clamp section in contracted angular relation, an operating lever connected to the said pivot, a cutter projecting from the inner end of the operating lever and operable to puncture the can end to form a pouring opening, a pair of cutter levers pivotally mounted in longitudinally spaced relation on the clamping arm, a slot cutting element formed on the inner end of each of the said levers, and a bar connecting the said cutter levers with the

operating lever whereby operative movement of said operating lever actuates the cutters to simultaneously puncture the can end at diametrically opposite points.

5. 4. In a can opening device, a clamp section having jaw means adapted to grip the rim of a can, a clamp arm pivotally connected to the said section adapted to extend transversely of a can top and having a rim gripping jaw at its outer end, a spring mounted at the said pivot connection having its ends bearing against the clamp section and arm respectively for yieldingly holding the jaws thereof in contracted relation, means formed on the clamp section in engagement with the arm for limiting the jaw contracting movement thereof, an operating lever pivotally connected to the clamp section and yieldingly held in a position at approximately right angles thereto, a cutter at the inner end of the said lever operable to puncture the can top to form a pouring outlet when the lever is swung downwardly, a lever pivotally mounted on the outer portion of the clamp arm, a cutting spur formed on the inner end of the said lever, and a connecting bar having one end pivotally connected with the cutter lever and its opposite end pivotally joined to the operating lever for operation of both cutters for puncturing the can top upon downward swinging movement of the operating lever.
